UNITED STATES PATENT OFFICE.

EMILE BERLINER, OF BOSTON, MASSACHUSETTS.

RESONATOR FOR VIOLINS.

SPECIFICATION forming part of Letters Patent No. 242,104, dated May 31, 1881.

Application filed August 9, 1880. (No model.)

To all whom it may concern:

Be it known that I, EMILE BERLINER, of Boston, county of Suffolk, State of Massachusetts, have invented a new and useful Improvement in Violins, of which the following is a specification.

My invention relates to the whole class of instruments which consist, like the violin, in the main, of a wooden box with convex bottom 10 and top, known as "belly" and "back," a limited number of strings, a tail-piece to which they are secured, and a finger-board for the determination of the pitch of each tone.

In the drawings, Figure 1, B is the belly. 15 G D A E are the strings. C is the bridge. F is the finger-board, and T is the tail-piece.

The merit of each violin and its value depends upon the purity and richness of its tone; and although one violin appears to look very 20 much like any other, their qualities differ greatly, due to certain manipulations in the way of making them, the kind of wood used, and other points of more or less value, which together make it difficult to produce first-class 25 instruments, while my improvement has for its purpose the lessening of this difficulty.

As may be seen, there are actually two sets of strings, each of a different composition and situated on both sides of the bridge C; but 30 although in practice only the longer set is played upon it will be evident that the shorter strings will occasionally vibrate when tones are being played which are in resonance with them. Moreover, since the tail-piece is usually 35 fixed to the violin by a mere string or cord, the shorter strings are apt to vibrate continuously, due to the general reverberation of the instrument while it is being played. The finger-board, too, forms in itself a wooden reed, which, 40 though stiff, is capable of vibration of its own while the violin is being played upon, and emits tones of different pitches, which, however, are not easily observable, on account of their weakness. It appears, therefore, that in 45 many cases where violins sound harsh and impure it is due to the interference with the tones played of over-tones, under-tones, or by-tones, from the causes above described; and in order to partly overcome these defects I support 50 both the tail-piece and the finger-board, so that their vibrations become more limited. This I accomplish in the case of the tail-piece by the

resonator M, and in the case of the finger-board by the resonator N. These resonators consist of arch-like supports made of wood, 55 metal, or other suitable material, formed similarly to the figures 2 and 3, and which, while resting with their ends upon the flanges of the violin, support the tail-piece and the finger-board in their respective middles. In the resonator M a screw, O, is added, to vary at will the pressure of the support, and such a screw may also be employed with the resonator M. These resonators not only aid in rendering the 60 tone of the instrument purer, but they communicate the vibrations of the strings more completely to the body of the violin and increase the loudness of the tone. In fact, by 65 their means an instrument hitherto considered weak and inferior can be made to emit very 70 pure and sonorous tones without the player being an artist.

The form of the resonators is such as to harmonize with the structure and appearance of the violin, as, according to celebrated makers, 75 the quality of a violin is partly dependent upon the beauty and symmetry of its curves and outlines. Hence I produce on the resonators such curvilinear outlines and forms as the concave curves W and Y, or similar ones, to 80 harmonize with one another and with the outlines of the violin.

The tail-piece T and its resonator may be formed in one piece, as shown in Fig. 3.

What I claim is—

1. In combination with a violin or similar instrument, the resonator N, arranged to support the finger-board, substantially as and for the purpose set forth.
2. In a violin or similar instrument, the resonator M, arranged to support the tail-piece, substantially as and for the purpose set forth.
3. In combination with the violin-resonator, the screw O, as and for the purpose set forth.
4. The violin-resonator having the curves 95 W and Y, as and for the purpose set forth.
5. The combination, with the violin, of a resonator of arch-like shape, as and for the purpose set forth.

EMILE BERLINER.
